UNITED STATES PATENT OFFICE.

HENRY F. STARRETT, OF CHICAGO, ILLINOIS, ASSIGNOR TO STARRETT MANUFACTURING COMPANY, OF CHICAGO, ILLINOIS, A CORPORATION OF ILLINOIS.

PANEL-BOARD CONSTRUCTION.

1,321,487.

Specification of Letters Patent. Patented Nov. 11, 1919.

Original application filed June 13, 1911, Serial No. 632,883. Divided and this application filed June 6, 1917. Serial No. 173,147.

To all whom it may concern:

Be it known that I, HENRY F. STARRETT, a citizen of the United States, residing at Chicago, in the county of Cook and State 5 of Illinois, have invented new and useful Improvements in Panel-Board Construction, of which the following is a full, clear, concise, and exact description, reference being had to the accompanying drawing, 10 forming a part of this specification.

My invention relates to improvements in panel-board construction.

One of the objects of my invention is to provide improved means for mounting the 15 switches on the face of the panel-board. Further objects will appear from the detailed description to follow and from the appended claims.

For the purpose of disclosing my invention, I have illustrated two embodiments 20 thereof in the accompanying drawings, in which—

Figure 1 is a front elevation of a panel-board construction showing a switch and 25 fuse-receptacles mounted thereon;

Fig. 2 is a section on the line 2—2 of Fig. 1;

Fig. 3 is a vertical section of a panel-board showing a modified construction of 30 the switch and fuse-receptacle mounting; and

Fig. 4 is a detail perspective of one of the contact clips.

Referring now to the drawings in detail, 35 and first to the form shown in Figs. 1 and 2, the panel-board construction here shown comprises a panel-board section 10 on which various circuit arrangements and fuse-devices may be arranged, and an extension section 11 connected to the section 40 10 and which in the present instance is shown as carrying a fused main-line switch.

I have illustrated in Figs. 2 and 3 two methods of mounting the switches and fuse- 45 receptacles. In Fig. 2 the method is the preferred form, wherein the switch may be attached or removed from the front of the board without disturbing any distributing circuits. As the method for mounting the 50 contact clips of the switch and the fuse-receptacle clips is the same, I will refer specifically to only the switch mounting for description.

The anchor-stud 12 for mounting the

pivot-post 13 of the switch on the insulating 55 base 14 of the section 11 is similar in construction to the anchor-stud 5 described in my prior application Serial No. 632,883, filed June 13, 1911, title panel-board, of which application this present application 60 is a division and continuation.

As shown in Fig. 2, the anchor-stud 12 is headed at 15 and has a portion 16 extending through a hole in the base 14. The lower end of this stud is restricted and screw-threaded, as at 17, and is adapted to receive a nut 18 for assisting in holding the anchor-stud in position on the base. Preferably interposed between the nut 18 and the base 14 is a washer 19. The conducting members or bus-bars 20 are provided with openings at the proper position to fit over the screw-threaded portion 17, and after the conductor is placed in position it is secured by a casting process; that is, a mold is secured in position over the end of the stud 12 and a securing metal—which may be brass or any other desired soldering metal—is poured into the mold, thereby joining the conductor member and the stud by a solid 80 mass and forming an integral metal conductor.

The front of the anchor-stud 12 has a screw-threaded opening, as at 21, to receive a screw 22 which extends through an opening in the offset base 23 of the pivot-post 13 for securing the pivot-post to the base 14. By providing this offset portion 23 I am enabled to obtain ready access to the screw 22 by means of a screw-driver or other operating means. By this construction the pivot-post 13 carrying the switch-lever 24 can be removed from the base 14 from the front side without disturbing the distributing circuits in the rear, simply by removing the screws 22.

The panel-board section 11 comprises, in addition to the insulating base 14, a backing 25 the edges of which fit against the base 14 and between which and the base 14 the 100 distributing circuits are inclosed. After the electrical connections have been made the backing 25 is placed in position, an insulating compound 26 is poured in, which completely fills the chamber between the base 14 105 and the backing 25, and in which the distributing conductors on the back of the base 14 are embedded.

The anchor-studs 27 on which the fuse-receptacle clips 28 are mounted are similar in construction to the anchor-studs 12 on which the pivot posts 13 are mounted, with the exception that the studs 27 are each provided with two slots 29 in their heads. The fuse connection-terminal is, in general construction, similar to the fuse connection-terminal at present manufactured and comprises a base member 30 having upstanding spring contact receptacle members 31. The base member, however, is provided with a pair of downwardly-extending projections 33 which are preferably formed by striking down a portion of the metal of the base. These two projections or lugs are adapted to fit into the slots 29 on the anchor-studs 27 to prevent the fuse-receptacle clips from turning.

20 The wire connection-terminals 34 of the section 11 are similar in construction to the wire connection-terminals of the panel-board shown in my earlier application Serial No. 632,883 referred to above, and need not be herein specifically described.

In addition to the wire connection-terminals 34, I may provide connection-terminals 35 by which the section 11 may be connected with the section 10. These connections are 30 similar in construction to the various anchor-studs shown in my prior application referred to, and described in connection with the mounting for the pivot-post 13 and need not be herein specifically described.

35 In connecting the section 11 to the section 10 the wire connection-terminals are removed from the section 10 and the sections 10 and 11 are connected together mechanically and electrically by means of connection-strips 36, which it will be noted are secured in position by the removable screws 37 of the anchor-studs.

In Fig. 3 I have illustrated a different method of securing the fuse-contacts and switches in position. In this form a small screw 38 is provided, which extends through an opening in the base 39 and is headed over the base 30 of the fuse-receptacle. The switch contact members and posts are secured in position by being provided with extension screws 40, which extend through and are connected to the bus-bars 41 in a manner which has been described with respect to the connecting posts 5 of my earlier application and also with respect to the anchor-studs 12 of the form of my invention shown in Figs. 1 and 2 of this present application. This method does not permit the removal from the front of the board of 50 the fixed contacts and fuse-contacts.

I have described the specific construction of fixed contacts in connection with the separable section of the board. It will be understood, however, that in the event it is desired to use switches on the panel-board in

connection with the branch extensions shown in my parent application, these switches may be mounted in the manner described with respect to the extensions; likewise, if it is desired to use fuse-receptacle contacts for the 70 N. E. C. fuses, the fuse-contacts or contact-receptacles such as described with respect to the separable section of the board may be used on the panel-board; also, if desired, the Edison fuse-receptacles may be used on the 75 separable portion of the board. In fact, the various anchor receptacles and other portions are interchangeable and may be used wherever desired.

What I claim as new and desire to secure 80 by Letters Patent of the United States is:

1. In a switch, a plate of insulating material, conductors supported by said plate and concealed from the front, main connection-terminals electrically connected in series 85 with said conductors, accessible for making an electrical connection from the front of the panel, a switch electrically connected in series with said conductors, means for detachably securing said switch in position on 90 said plate accessible from the front of the plate for attaching and detaching the switch, and means for holding said conductors in position with respect to said panel independently of said securing means for the 95 switch.

2. In a switch, an insulating plate, anchorage and conductor means supported by said plate and extending therethrough, conductors at the rear of said plate electrically connected in series to said anchorage and conductor means, main line terminals positioned on the front of said plate and connected in series to said conductors, and a switch electrically connected in series with said conductors supported on the front of said plate and detachably connected with said anchorage and conductor means and removable from the front of the plate without disturbing said conductors. 100

3. In a switch, an insulating plate, anchorage and conductor means supported by said plate and extending therethrough, conductors at the rear of said plate electrically connected in series to said anchorage 115 and conductor means, a switch supported on the front face of said plate, said switch comprising a fixed contact electrically connected in series with said conductors and detachably connected with said anchorage and conductor means and removable from the front side of the plate without disturbing said conductor means.

4. In a switch, an insulating plate, conductors supported at the rear of said plate, 120 and conductors at the front of said plate, a switch supported on the front face of said plate, said switch comprising a fixed contact electrically connected in series with said conductors and detachably connected with said anchorage and conductor means and removable from the front side of the plate without disturbing said conductor means. 125

5. In a switch, an insulating plate, conductors supported at the rear of said plate, 130

anchorage and conductor means supported by said plate and extending therethrough comprising an internally-threaded member, a switch mounted on the front face of said 5 plate, and means electrically connecting said switch in series with said conductors and mechanically connecting it with said anchorage means comprising a member threaded into said internally-threaded 10 member, whereby said switch can be attached to and detached from said anchoring means without disturbing said conductors.

5. In a device of the class described, an insulating base, anchor studs of conduct-

ing material supported thereby and extending therethrough, a system of conductors supported by said base and concealed from the front thereof and electrically connected in series with said anchor-studs, a circuit-controlling switch supported on the front 20 face of said base, and means for mechanically connecting said switch with said anchor studs accessible for removal from the front of said base, said means connecting said switch in series with said anchor studs. 25

In witness whereof, I have hereunto subscribed my name.

HENRY F. STARRETT.
